Aaron Chandler
Inventor.

United States Patent Office.

AARON CHANDLER, OF DAVENPORT, IOWA.

Letters Patent No. 94,473, dated September 7, 1869.

IMPROVED SCHOOL-DESK AND SEAT.

The Schedule referred to in these Letters Patent and making part of the same.

To all whom it may concern:

Be it known that I, AARON CHANDLER, of Davenport, Iowa, have invented a new and useful Improvement in School-Desks and Seats; and I do hereby declare the following to be a full and exact description thereof, reference being had to the accompanying drawings, in which—

Figure 1 is a perspective view of my desk and seat;

Figure 2 is a detached sectional view of the hinge, seat, arm, slot, and standard;

Figure 3 is a plane front view;

Figure 4 is a side elevation of the desk, showing the book-box held in a horizontal position by means of a locking-device; and

Figure 5 is a side elevation of the desk, with the book-box thrown down in a vertical position.

The same letters of reference indicate corresponding parts in the several figures.

The nature of my invention consists in having the standards of a school-desk provided with slotted or wedge-shaped lugs, for supporting the arms of the seat when in a horizontal position; also, an automatic locking-device for supporting the book-box, when in a horizontal position, hereinafter more fully described.

A represents a book-box, the end pieces of which are made of metal.

S S are the standards, to which is secured the seat-back G.

B are the seat-arms or supports.

C is the lug on the standard S.

D is the slot in the lug C.

H is the seat.

I construct my seat as follows:

The seat-arm B is constructed in the usual form, with a rim or projection passing downward. The seat is hinged in any convenient manner upon the projection E, upon the standard S. The lug C has a deep wedge-shaped notch, or slot D, cut in it from the top, to receive the lower or sharp part of the arm B, when the seat is let down. This slot is not as wide at its lower part as the thickness of the arm that rests in it, so that the arm rests against the sides of the slot, and not on the bottom thereof. When it is desired to have the seat out of the way, it is simply folded upward and backward, as at fig 3. When it is desired

to use the seat, it is let down so that the arm B of the seat rests in the wedge-shaped slot D, thus acting as a support for the seat, and wedging down into the slot, so there is no lateral motion in either direction. It also deadens the noise of the falling seat.

The automatic locking-device consists in a sliding bolt or bar, N, working in a slot on the standard, and held in place by a cross-piece, or strip O, as clearly shown in figs. 4 and 5.

The book-box is provided with two pins P P', on each side, working in corresponding slots or grooves a a' in the standards S. When the book-box is raised in a horizontal position, the pins rest in the recesses or shoulders R R'.

The operation is as follows:

When the book-box is to be raised in a horizontal position, the lower pin P, on one side of the book-box, raises the sliding bolt, or bar N, until the pins are about level with the recess, or shoulder R, in the standard. Then the book-box is to be pushed forward on the shoulders, which releases the sliding bolt or bar, and allows it to drop down into its original position, thus entirely enclosing the pin T in the recess, or shoulder R. When the book-box is to be lowered, the sliding bolt or bar is raised, and the book-box is pressed back until the pins are off from the shoulders, which allows the pins to slide down the grooves or slots in the standards S S, which brings the book-box into a vertical position.

Having thus described the nature, construction, and operation of my invention,

What I claim therein as new and useful, and desire to secure by Letters Patent, is—

1. The standards S S, provided with the slotted or wedge-shaped lugs C, in combination with the arms B of the seat H, constructed as herein described, for the purposes specified.

2. The automatic locking-device N, when used in combination with the book-box A and slotted standard S, constructed and arranged to operate as herein described, for the purposes specified.

AARON CHANDLER.
